UNITED STATES PATENT OFFICE.

REES PRICHARD, OF DETROIT, MICHIGAN.

PORTABLE FRAME FOR MOSQUITO-BARS.

1,279,434.

Specification of Letters Patent. Patented Sept. 17, 1918.

Application filed June 22, 1918. Serial No. 241,383.

To all whom it may concern:

Be it known that I, REES PRICHARD, a citizen of the United States, residing at Detroit, in the county of Wayne and State of Michigan, have invented new and useful Improvements in Portable Frames for Mosquito-Bars, of which the following is a specification.

This invention relates to portable frames for mosquito bars, the particular object of the invention being to provide a portable frame structure which is also capable of being compactly folded for storage and transportation, enabling the complete device to be carried as a part of a camping outfit or equipment, the device being also useful in all places where it is desirable to protect the head, neck or face of a person while reclining or sleeping.

With the above and other objects in view, the invention consists in the construction, combination and arrangement of parts, as herein described, illustrated and claimed.

In the accompanying drawings:

Figure 1 is a perspective view showing the device in its applied relation to a cot or couch.

Fig. 2 is a plan view of the frame of the device.

Fig. 3 is a rear elevation thereof.

Fig. 4 is an end view of the same.

Fig. 5 is a perspective view of the bar or net proper.

Fig. 6 is a perspective view of the frame when folded.

The portable mosquito bar frame contemplated in this invention comprises a pair of U-shaped end members each designated generally at A and comprising an upright bar 1 and upper and lower normally horizontal bars 2 and 3 extending at a right angle to the upright bar 1 and rearwardly from said bar 1 when the complete frame is in its useful position.

The rear portion of the frame is also composed of two U-shaped members, each of which is designated generally at B, each of said members comprising an upright bar 4 and upper and lower normally horizontal

bars 5 and 6 respectively, which extend inwardly from the upright bar 4. The inner extremities of the bars 5 and 6 of the members are formed with eyes 7 through which are inserted pivots 8, the upper and lower

pivots 8 being arranged in vertical alignment with each other, so that said rear portion of the frame structure may be folded at a central point. The horizontal bars 5 and 6 are also connected between the ends thereof by vertical braces 9, the upper and lower extremities of which are formed into eyes 10 which embrace said upper and lower horizontal bars 5 and 6. The rear extremities of the upper and lower bars 2 and 3 of the end frames A are formed with eyes 11 to receive the adjacent vertical bar 4 of the contiguous section of the rear frame member B, thus forming a pivotal connection between the end frame sections and the rear frame sections, to assist in the folding operation of the complete frame structure.

The lower horizontal bars 3 of the end frames A are connected by a strip 12 of fabric, such as canvas, the end portions of the canvas being formed with hems 13 through which the bottom bars 3 are inserted. The strip 12 forms what may be termed a flexible bed piece for the foldable frame and limits the movement of the end frames away from each other. In connection with the frame, thus far described and the flexible bed piece or strip 12, I employ stretching members 14 as best illustrated in Fig. 2, each of said members being connected by a pivot 15 to the top bar 2 of one of the end frames, and said stretcher members 14 being connected together at their inner overlapping ends by means of a pivot 16, by moving the stretcher members 14 into longitudinal alignment with each other, as shown in Fig. 2, the flexible bed piece 12 is stretched taut and the frame structure is also braced in its useful position. It is designed to place a pillow upon the flexible bed piece 12, and then to place over the entire frame structure a mosquito bar or net designated generally at 17, the same being formed to properly embrace the frame structure, previously described, and embodying in this construction a flexible base or bed piece 18 which is designed to be placed under the flexible bed 12 and between the latter and the mattress or supporting surface of the cot or couch in conjunction with which the device, as a whole, is used. The weight of the head of the occupant thus serves to hold the frame structure in place and also confine the net or mosquito bar in its proper place. Sufficient fullness is allowed in the mosquito

bar to enable the same to be draped over the chest of the occupant of the cot or couch.

I claim:—

1. A portable mosquito bar frame, embodying a pair of U-shaped end frame members, another pair of U-shaped members arranged at the rear of said end members and connected therewith on vertical axes, said rear frame members being connected at their adjacent ends by vertical pivots arranged one above the other, a flexible bed piece connecting the lower portions of the end frame members, and serving to limit the outward movement of said end frame members, stretching means connecting said end frame members for pressing the latter away from each other, and tensioning the flexible bed piece.
2. A portable mosquito bar frame, embodying a pair of U-shaped end frame members, another pair of U-shaped members arranged at the rear of said end members and connected therewith on vertical axes, said rear frame members being connected at their adjacent ends by vertical pivots arranged one above the other, a flexible bed piece connecting the lower portions of the end frame members, and serving to limit the outward movement of said end frame members, and stretching means connecting said end frame members for pressing the latter away from each other and tensioning the flexible bed piece, said stretching means comprising a pair of stretching members pivotally connected at their outer ends to the end frame members and having their inner ends overlapped and pivotally connected centrally of the frame structure, and in transverse alignment with the pivotal connection of the rear frame members.

nected at their outer ends to the end frame members and having their inner ends overlapped and pivotally connected centrally of the frame structure, and in transverse alignment with the pivotal connection of the rear frame members.

3. A portable mosquito bar frame, embodying a pair of U-shaped end frame members, another pair of U-shaped members arranged at the rear of said end members and connected therewith on vertical axes, said rear frame members being connected at their adjacent ends by vertical pivots arranged one above the other, a flexible bed piece connecting the lower portions of the end frame members, and serving to limit the outward movement of said end frame members, stretching means connecting said end frame members for pressing the latter away from each other and tensioning the flexible bed piece, said stretching means comprising a pair of stretching members pivotally connected at their outer ends to the end frame members and having their inner ends overlapped and pivotally connected centrally of the frame structure, and in transverse alignment with the pivotal connection of the rear frame members, and a mosquito bar shaped to fit over and inclose said frame structure, said mosquito bar comprising a flexible bed piece adapted to underlie the flexible bed of the frame structure.

In testimony whereof I affix my signature.
REES PRICHARD.
